UNITED STATES PATENT OFFICE.

GEORGE WHITE, OF JERSEY CITY, NEW JERSEY.

TRANSFER-PRESS.

No. 821,911.

Specification of Letters Patent.

Patented May 29, 1906.

Application filed June 17, 1904. Serial No. 213,050.

To all whom it may concern:

Be it known that I, GEORGE WHITE, a citizen of the United States, residing in Jersey City, in the county of Hudson, in the State of

5 New Jersey, have invented certain new and useful Improvements in Transfer - Presses, &c., of which the following is a specification, reference being had to the accompanying drawings, forming a part thereof.

10 In another application, filed September 19, 1903, Serial No. 173,771, there is described a compact rigid machine for the transfer of lines or characters from a previously-prepared master-roll to a copper plate in intaglio, that the latter may be used for printing, such machines being so constructed and arranged as to permit the master-roll and the plate to be brought progressively nearer to each other. For the practical operation of 15 such machine upon a commercial scale it is found desirable to provide means for quickly and exactly adjusting the master-roll to its proper position, and with the attainment of such result the present invention is concerned.

20 The invention will be more fully described hereinafter with reference to the accompanying drawings, in which it is illustrated, and in which, as far as possible, parts which are 25 common to the machine described in said former application and to the machine herein shown and described are identified by the same letters of reference.

25 In said drawings, Figure 1 is a view in elevation of one end of the improved machine. Fig. 2 is a plan view with the sides of the frames and some other parts in horizontal section.

30 Except as hereinafter pointed out, the construction of the present machine is substantially the same as described in said former application. The frame comprises webbed top and bottom plates *a* and side plates *b*, secured together by bolts *c*. A working plate *a'* for contact with the master-roll *e* may be 35 secured to the under side of the top plate *a*. A wedge *f*⁴ is arranged to be driven or retarded by a screw operated by a suitable hand-wheel *f*², such wedge supporting a vertically- 40 movable block *g*, upon which is supported for longitudinal movement in a horizontal plane a second block or plate *h*, the same being moved by a screw operated by a suitable hand-wheel *h*⁴, while rolls *h*⁵, held in position 45 by the frame *h*⁶, are interposed between the vertically-movable block *g* and the longitudi-

nally-movable block *h*. Upon the block *h*, which is reciprocated for the purpose of effecting the transfer of lines or characters from the master-roll *e* to the copper plate, is 50 further supported an adjustable supporting-plate *k*², arranged to be moved longitudinally for the purpose of adjusting the copper plate in position and for permitting the withdrawal of the same from the machine for examination or substitution by a screw operated by a suitable hand-wheel *k*³. The copper plate *l*, which is to receive the impression, lies upon the top of the adjustable plate *k*² and reciprocates in contact with the master-roll *e* as the block or plate *h* is reciprocated and may also be withdrawn from beneath the master-roll *e*, with the adjustable plate *k*², by 55 operating the hand-wheel *k*³.

The master-roll *e* is pressed upward against 60 the working plate *a'* by supporting-blocks *m*⁸, which may be pressed upward by the lever *m* and springs. (Not shown in the accompanying drawings.)

The parts thus far referred to are arranged 65 and operate in the same manner as the corresponding parts of the machine described in the former application above referred to, and it will not be necessary to enter into a more detailed explanation of the construction and 70 relation of these parts. That with which the present invention is particularly concerned is the means by which the master-roll *e* may be introduced into the machine and quickly 75 and easily adjusted to the exact position required for operation. These means will now 80 be described. Upon the side plates *b* of the machine are secured brackets *b*', which support rails or tracks *b*², upon which may travel a carriage which receives the master-roll *e*. As shown in the drawings, this carriage 85 comprises side frames *n*, transverse bars *n*', and wheels or rollers *n*², which may be mounted upon the ends of one of the bars *n*'. To guide the carriage in its movements and 90 to insure its parallelism, one of the transverse bars may be provided centrally with a rod *n*³, which passes through a guide-plate *o*. The latter is mounted upon pivots *o*' in brackets *o*², secured to the side plates of the machine, 95 to allow for a variation in position of the carriage in a vertical plane without binding.

The opposite side frames *n* of the carriage are provided with center screws *n*⁴, which are adapted to engage the master-roll *e* in the line 100 of its axis and maintain it axially in definite 105 and unchanged relation with respect to the

carriage. Since the parallelism of the latter is assured, as already described, the roll itself is therefore maintained in parallel relation with the transverse axis of the machine while it is being placed in operative position in the machine and is maintained absolutely in such relation until it is held by the supporting-blocks m^8 , before referred to. Furthermore, in order that the master-roll may be so placed in the machine that the line of characters thereon to be transferred to the copper plate shall be exactly in the required position when the operation of transferring is begun there is provided a pin p , arranged to slide in a fixed bearing in a bracket p' , secured to one of the side plates b of the machine, and to pass through the adjacent side plate n into a recess e' , formed therefor in the adjacent end of the master-roll e .

It is unnecessary to explain herein at length the operation of the machine as a whole. So far as the operation of the device herein particularly referred to is concerned, it will be understood that when the master-roll e has received the characters which are to be transferred it is placed in the carriage, which has been drawn out to receive it, the center screws n^4 being turned in to engage the countersinks in the ends of the roll. The carriage is then moved inward, its rod n^3 engaging the guide o , until it is brought to the desired position above the plate k^2 . The roll is then rotated until the pin p can be inserted into the recess e' formed in the end of the roll e and the correct position of the roll assured. The pin p is then withdrawn and the supporting-blocks m^8 are raised, as described in said former application, to engage the roll e and press it upward against the working plate a' .

When this is accomplished, the roll is reciprocated with a rolling movement upon the copper plate, as described in said former application. In other respects the operation of the machine herein described does not differ from that of the machine described in said former application.

It will be understood that it is not intended to limit the invention to the precise construction and arrangement of parts shown and described herein, as it is obvious that the same may be varied to suit different conditions of use without departing from the spirit of the invention.

I claim as my invention—

- 55 1. In a transfer-press, the combination of a frame, a working plate and a plate-supporting block movable vertically, the one with respect to the other, a master-roll carriage and a track or ways upon which the carriage with the master-roll may be guided to position between the working plate and the plate-supporting block, substantially as described.
- 60 2. In a transfer-press, the combination of

a frame, a working plate and a plate-supporting block movable vertically, the one with respect to the other, a master-roll carriage, a track or ways upon which the carriage with the master-roll will be guided to position between the working plate and the plate-supporting block and a guide for said carriage, substantially as described. 65

3. In a transfer-press, the combination of a frame, a working plate and a plate-supporting block movable vertically, the one with respect to the other, a master-roll carriage, a track or ways upon which the carriage with the master-roll will be guided to position between the working plate and the plate-supporting block a guide-rod secured to said carriage, and a guide-block mounted on the frame, substantially as described. 75

4. In a transfer-press, the combination of a frame, a working plate and a plate-supporting block movable vertically, the one with respect to the other, a master-roll carriage, a track or ways upon which the carriage with the master-roll will be guided to position between the working plate and the plate-supporting block a guide-rod secured to said carriage, and a guide-block pivotally mounted on the frame, substantially as described. 80 90

5. In a transfer-press, the combination of a frame, a working plate and a plate-supporting block movable vertically, the one with respect to the other, a master-roll carriage, a track or ways upon which the carriage with the master-roll may be guided to position between the working plate and the plate-supporting block, and a positioning-pin adapted to engage one of the side frames of the carriage 95 and the master-roll, substantially as described. 100

6. In a transfer-press, the combination of a frame, a working plate and a plate-supporting block movable vertically, the one with respect to the other, a master-roll carriage, a track or ways upon which the carriage with the master-roll may be guided to position between the working plate and the plate-supporting block, and a positioning-pin mounted on the frame and adapted to engage the master-roll, substantially as described. 105 110

7. In a transfer-press, the combination of a frame, a working plate and a plate-supporting block movable vertically, the one with respect to the other, a master-roll and a positioning-pin mounted on the frame and adapted to engage the master-roll, substantially as described. 115

This specification signed and witnessed 120 this 13th day of April, A. D. 1904.

GEORGE WHITE.

In presence of—

GEORGE WHITE, Jr.,
JAMES F. FIELDER.
